Primary Examiner — Rosemary K Tarcza*Assistant Examiner* — Nathaniel D. Buckner(74) *Attorney, Agent, or Firm* — NSIP Law(57) **CLAIM**

We claim the ornamental design for a charging case for wireless earphones, as shown and described.

DESCRIPTION

FIG. 1 is a front perspective view of a charging case for wireless earphones showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is the front perspective view thereof showing an example state of use.

The broken lines in the figures depict portions of the article which form no part of the claimed design.

1 Claim, 5 Drawing Sheets(56)
